ELECTRIC CIRCUIT CONTROL MECHANISM

Charles L. Paulus, Dayton, Ohio

Application July 25, 1941, Serial No. 404,028

12 Claims. (Cl. 200—4)

(Granted under the act of March 3, 1883, as amended April 30, 1928; 370 O. G. 757)

The invention described herein may be manufactured and used by or for the Government for governmental purposes, without the payment to me of any royalty thereon.

This invention relates to mechanism for the selective control of a number of electric circuits and is particularly applicable to remote control of electrically operative instrumentalities. It is herein embodied in a unit for the control, by selected radio signals, of the movements of a distant body such as an airplane, aerial target, aerial torpedo, land or water vehicle, or the like.

An object of the invention is to provide, in a device of this character, an arrangement of contact members which will have sufficient yieldability to produce a wiping engagement yet will be positive in their engagement and not subject to maladjustment from distortion of the parts.

Another object is to provide a multiple contact switch mechanism which normally is resiliently biased to a positively located "off" position in which all contacts are disengaged, in order that no contacts will be or remain engaged except by an intentional effort on the part of the operator.

Another object is to so construct and arrange the manually operable selective engaging means that separate contacts are effected by movement in different directions, to the end that the possibility of simultaneously making two contacts having opposite effect is obviated.

Another object is to provide simple and effective adjusting means for the switch parts whereby the "off" position, to which the device is normally constrained, may be readily maintained.

Another object is to so design the manually operable portion of the device that all of its functions may be performed without moving the hands from one position to another.

Another object is to so construct and arrange the control switch and its operating means that there will be no loose or exposed wires on the outside of the mechanism.

Another object is to so design the manually operable contact making means that its several movements will readily be associated with the results attained, to the end that the likelihood that the operator will execute an unintended movement will be minimized.

That these and other objects and advantageous features are attained will become evident as the detailed description proceeds, reference being had to the drawings, wherein,

Fig. 1 is a front perspective view showing the exterior of an assembled switch and its actu-

ating mechanism made according to the invention.

Fig. 2 is a front elevation with parts broken away to show the interior structure.

Fig. 3 is a horizontal section through the switch taken at 3—3 of Fig. 2 shewing the interior mechanism in plan view.

Fig. 4 is a vertical section taken at 4—4 of Fig. 2.

Fig. 5 is a vertical section taken at 5—5 of Fig. 3.

Fig. 6 is a fragmentary section through the control wheel hub taken at 6—6 of Fig. 5.

Fig. 7 is a fragmentary section through the contact blades, taken at 7—7 of Fig. 3.

Fig. 8 is a fragmentary section through the contact blades, taken at 8—8 of Fig. 2.

Fig. 9 is a perspective view showing one of the contact blades in detail.

Fig. 10 is a perspective view showing one of the locating sleeves in detail.

In the drawings, a frame 11 is provided with bearing bosses 12 within which a rock shaft 14 has limited axial as well as rocking movement.

Substantially midway between the bosses 12, the shaft is grooved transversely from the top downward to provide a seat for the rocking bar 16, and in the same axial position, the shaft is grooved transversely from the bottom upward for a stop member 18 having a depending portion 19 which is instrumental in maintaining the normal axial position of the shaft. A single screw 20 extends through a clearance hole in the bar 16 and into a tapped hole in the member 18 to hold both parts 16 and 18 to the shaft.

35 A cross hole 22 through the part 19 facilitates tapping of the member. A wire 24 locks the screw against unintentional loosening.

Outside and in front of the frame 11, an operating wheel 26 having spokes 27 and a rim portion 29, is secured to the forward end of the shaft 14, the forward end being tapered as at 28, and the opening in the hub 30 of the wheel being correspondingly tapered and drawn up on the shaft taper by the screw 32. Screw 32 extends into a tapped hole in the front end of the shaft. A key 34 secures the wheel against rotation on the shaft.

Cooperating with the stop member 18 (see Fig. 5) in maintaining the shaft 14, in a normal unoperated position, is a pair of horizontally disposed sleeves 36 (see Fig. 10). These sleeves are slidable in openings in bosses 12, the openings being below and axially parallel to the shaft. 55 The outer ends of the openings are counterbored

to a larger diameter, thereby providing a shoulder 33, the counterbored portion being tapped as at 49. Sleeves 36 are provided at their outer ends with flanges 42 which are freely movable within the tapped portion 49. Peel shim washers 44 are inserted between the flanges 42 and the shoulders 33. Springs 48 urge the sleeves inward until the flanges are arrested by the shim washers. The washers should be of such thickness as will allow the inner ends of the sleeves to just lightly touch the depending portion 19 of the locator leaving it freely slideable between the inner ends of the sleeves. Screws 48 have long pilots 50 which extend through springs 46 and have slideable bearing in the inner ends of the sleeves at 47 (see Fig. 10). The outer ends of the screws 48 are multiple slotted and a novel wire locking means 52 is anchored in the frame and has its free end resiliently entered into one of the screw slots. Thus the freedom of the rocking movement of the part 19 between the ends of the sleeves 36 is governed by the thickness of the stack of shims 44, and the axial movement of the shaft 14 is limited by the part 19 encountering the ends of the pilots 50 when the shaft is axially displaced against the resistance of the springs 46. The assembled parts 36, 42, 44, 46, 48, 50 and 52 may be collectively referred to as a locator 51.

Co-operating with the underside of the rocking bar 16, in maintaining the bar in its level unoperated position, is a pair of vertically disposed sleeves 36 (see Fig. 10). These sleeves are slideable vertically in bored openings in bosses 54 in the bottom of the frame 11 (see Fig. 2). The bosses are bored at the top to slidably receive the sleeves 36 and counterbored from below to receive the flanges 42. Except for being vertically instead of horizontally disposed, the vertical locators 51 which co-operate with the underside of the rocking bar 16 are exactly like the horizontal locators 51 previously described, which co-operate with the depending portion 19 of the stop 18.

The peel shim washers 44 of the vertical locators (see Fig. 2) are made of such thickness as will allow the upper ends of the sleeves 36 to just lightly touch the bottom surface of the rocking bar 16, whereby the bar is normally held in its horizontal position, while the screws 48 are so adjusted that the desired rocking movement of the bar is had when the bottom surface of the bar encounters the upper rounded ends of the pilots 50. Thus it will be seen that the sleeves 36 constitute yielding stops which define the neutral position of the bar while the screws 48 constitute non-yielding stops which limit bar movement to the operative position.

The rocking bar 16 carried a series of grounded contact members, which, by rocking or axial movement of the bar by the rock shaft, engage properly placed insulated contact members carried in the frame.

The rocking bar 16 has longitudinal channels or grooves on the top and two sides, as at 55, to slidably receive the grounded contact members 56 (see Fig. 9), each of which comprise a plate 58 with a central opening 60 and a contact point 62 riveted or similarly secured in the narrow end of the plate.

Near each end the rocking bar 16 has a pair of transverse openings, one horizontal for a stud 64 and the other smaller and vertical for a stud 66 (see Fig. 7), the stud 66 being shouldered with the smaller part extending through the

larger stud 64 and the rocking bar 16 and being riveted at 68.

The grounded contact members 56 fit freely in the grooves 55 and the holes 60 have considerable freedom over the studs 64 and 66. Springs 70 are held on the studs under an initial stress by the washers 72 and cotter pins 74 to thereby resiliently hold the contact members against the bottoms of the grooves.

10 Bosses 76 extending vertically from the bottom of the frame (see Fig. 2), and bosses 78 extending inwardly from the sides (see Fig. 3), are drilled and provided with press fitted dielectric bushings 80, the bushings being tapped for the threaded insulated contact studs 82.

15 Studs 82 each have an integral polygonal head 84 by which they may be adjusted, and a jam nut 86 by which they may be locked in the adjusted position, and, at the extreme outer end, carry a renewable contact point 88. Studs 82 may preferably be so adjusted that contact will be made between a movable grounded point 62 and a stationary insulated point 88 when about half the total movement of the grounded point, as allowed by the pilot 50 of an adjusting screw 48, has been completed. If the points 82 are adjusted in this manner then, after contact is made, further movement of the bar 16, either rocking or axial, will produce a lateral or wiping contact between the engaging points. The novel structure for accomplishing this desirable result is considered one of the meritorious features of the invention.

Near the upper ends of the rim portions 29 of the operating wheel 26 are two switches of more or less conventional design. The one on the left is spring biased to a midway or neutral position but operative, preferably with the thumb, to two other positions one above and one below the mid-way position. This switch may be called the throttle control switch and may be designated as a whole by the numeral 90. The one on the right is a substantially conventional tumbler switch having merely an "on" and "off" position. This switch may be called the level flight switch and may be designated as a whole by the numeral 92.

In order that there may be no loose or exposed conducting wires in the device, a unique arrangement for bringing conductors off of the switches 90 and 92 is provided. The rim portions 29 and spokes 21 being hollow, getting the conducting wires from the switches to the hub 30 presents no difficulty, but getting the wires past the hub, through the frame and out through the conduit fitting 94 requires a special arrangement.

55 The shaft 14 is provided with a central opening 96 at the rear end, and another, 98, at the front end, both serving to lighten the shaft, but the front opening 98 also serving as a wire passage.

60 The taper portion 28 of the shaft 14 is slotted through and into the passage 98 as at 100 and 102 (see Figs. 5 and 6), and wires from the switches 90 and 92 may thus be brought through the hollow passages 104 and 106, through the slots 100 and 102, into the passage 98 and out through the lateral opening 108 into the frame, from whence it may be taken along with other wires which will be attached to the insulated terminals 82 out through the opening 110 and conduit fitting 94 and through the conduit 95 which is also the supporting column of the device.

In order to form a closed housing around the 75 wires and the operative mechanism, a cover is

so attached to the frame 11 as to close the upper open portion thereof. The cover is preferably made in two parts 112 and 114 which overlap at 115 and are secured to the frame 11 by screws 116 and 118 respectively.

The auxiliary switch 120 which may also be called the beam control switch is contained in an extension 122 of the cover part 112. Switch 120 is a conventional two pole tumbler switch. The conducting wire extending therefrom may preferably be brought out through the fitting 94. The inspection of the interior of the switch may be accomplished by removing the rear half 114 only of the cover whereby the switch 120 and its connections will not be disturbed.

In using the device shown for the remote control of an airplane in flight, the switch 120 controls the circuit which projects the beam, the switch 90 is adapted, when closed, to send a signal which controls the throttle, and the switch 92 is adapted, when closed, to send a signal which controls the automatic level flight mechanism of the plane. The switch 120 may be closed before the operating wheel is grasped, and when the rim portions 29 of the wheel are grasped in the hands, the thumbs will be in position for operating the switches 90 and 92.

The insulated contacts 82 are so connected that those contacts which are closed when the wheel 26 is pushed or pulled axially forward or rearward control the signals for producing a dive or a climb respectively, while those contacts which are closed when the wheel is rocked clockwise or anti-clockwise control the signals for producing a right or a left turn.

The peculiar shape of the control wheel 26 which is in the form of a W provides considerable advantage where the device is used on one plane for controlling the movements of another plane, in that the lap room is considerably greater than it is with wheels of conventional design.

Having described the invention in relation to one of its applications, I claim:

1. Control mechanism comprising, in combination, a frame, a shaft rockable and axially slideable in said frame, operating means for said shaft, a rocking bar of rectangular cross section extending transversely across said shaft and secured thereto, said bar having channels extending longitudinally in three of its edges, grounded contact members each comprising a plate having a wide end fitted freely in a channel and a contact point at the narrower free end, one each contact member being provided at each end of each channel, spring means for resiliently holding the wide end of said grounded contact members in said channels, insulated contact members supported in said frame in alignment with, but normally not touching said grounded contact members, said insulated and grounded contact members comprising pairs, said pairs being relatively so positioned that two of the pairs may be engaged by axial movement of the bar in one direction from its normal position, two other of the pairs by axial movement of the bar in the other direction from the normal position, one pair by rocking the bar clockwise from its normal position and the remaining pair by rocking the bar anti-clockwise from its normal position, means to resiliently hold the bar in its normal position, and adjustable stops to limit both axial and rocking movement of said bar to amounts which are somewhat in excess of the movement necessary to engage the pairs of contacts.

2. The combination, in a control device, of a

frame, a bar in said frame arranged to rock about a transverse axis and move laterally along said axis, operating means for said bar, longitudinal channels in said bar, grounded contact members each having one end resiliently held in the outer end of one of the channels and the overhanging end provided with a contact point, insulated contact points held in said frame in position for engagement with some of said grounded contact points when said bar is rocked, insulated contact points held in said frame in position for engagement with some of said grounded contact points when said bar is moved axially, resilient means holding said bar to an "off" position and against both rocking and axial movement, and stops for limiting movement of said bar to an amount somewhat greater than that necessary to bring the insulated and grounded contact points together.

3. In a control mechanism, a frame, a bar supported in said frame so as to be rockable about a transverse axis and movable laterally in the direction of said axis, contact members having one end resiliently secured to the end of the bar and the other end overhanging and provided with a grounded contact point, insulated contact points positioned in said frame for engagement with said grounded contact points, operating means for rocking said bar to engage some of the contact points or moving it axially to engage other of the contact points, resilient means holding the bar to an "off" position, and stops limiting both the rocking and axial movement of the bar to a distance slightly greater than that necessary to engage said contacts.

4. In a device of the character described, a frame, a bar rockable about an axis transverse to its length in said frame and laterally movable along said axis, contact points of one polarity resiliently held on the bar near the end, contact points of the other polarity held in the frame in position for engagement with the bar contact points, operating means for rocking said bar to engage some of the contact points or moving it axially to engage other of the contact points, yieldable means for normally holding the bar with all contact points disengaged, and stops set to arrest both rocking and axial movement of said bar after said movement has progressed slightly beyond the point necessary to engage said contact points.

5. In a control device, a frame, a bar movable sidewise in said frame and rockable on an axis parallel to its sidewise movement, contact points of one polarity supported near the free end of the bar, contact points of the other polarity supported in the frame, one positioned to be engaged by a bar contact point when the bar is rocked and another positioned to be engaged by another bar contact point when the bar is moved axially, resilient means normally holding the bar with all contact points disengaged, resilient means associated with the contact points whereby slight additional bar movement may be had after the contact points engage, and adjustable stops for limiting said additional bar movement.

6. In a switch mechanism, a frame, a shaft rockable in said frame, a bar secured to said shaft, its length being transverse to the shaft axis, contact members engageable by rocking movement of said shaft and bar, manual means to rock said shaft and bar away from a neutral position, and means to return said shaft and bar to the neutral position which comprises two

sleeves each having the inner end normally extended so as to be substantially touching the bar, both on the same side but out from the rocking axis, and positioned, one to oppose rocking in one direction and the other to oppose rocking in the other direction, and means to prevent said inner ends being extended beyond their normal position, which comprises flanges at the outer ends of the sleeves, co-operating shoulders on the frame, peel shim washers between said flanges and said shoulders, and springs surging said flanges against said shoulders.

7. The structure of claim 6 with an adjustable screw extending centrally through each said sleeve and positioned to limit rocking movement of said bar away from the neutral position.

8. In a switch mechanism, a frame, a shaft axially slidable in said frame, a contact carrying member secured to the shaft, the contacts on said member being engageable with other contacts by axial movement of said shaft in either direction, manual means to axially move said shaft and member away from a neutral position, and means to return said shaft and member to the neutral position, which comprises a locating part on the member, two axially parallel sleeves on opposite sides of the locating part with their inner ends normally extended so as to be substantially against said locating part and with means for preventing said inner ends being extended beyond their normal position, which comprises flanges at their outer ends, co-operating shoulders in the frame, peel shim wash-

ers between said flanges and said shoulders, and springs for holding said flanges against said washers.

9. The structure of claim 8 with adjustable stops to limit the axial movement of said shaft and member in either direction away from the neutral position.

10. In a switch mechanism, a frame, a contact member movable in said frame in two directions from a neutral position, means to move said member in either direction, and mechanism for returning said member to the neutral position which comprises two yieldable stops, one positioned to oppose movement of said member in one direction away from neutral and the other positioned to oppose movement of the member in the other direction away from neutral, resilient means urging said stops toward said member, locating shoulders on said stops, co-operating locating shoulders carried by said frame and peel shims between said stop shoulders and said frame shoulders of a thickness to arrest movement of said stops by said resilient means when said stops substantially touch said member.

11. The structure of claim 10 with additional stops for limiting movement of the member away from neutral in either direction.

12. The structure of claim 10 with additional stops for limiting additional movement of the contact member away from neutral in either direction after contact has been made.

CHARLES L. PAULUS.
